UNITED STATES PATENT OFFICE.

JOHN W. WILKINSON, OF BEAUMONT, TEXAS, ASSIGNOR OF FORTY-NINE ONE-HUNDREDTHS
TO LOUIS MAYER, OF BEAUMONT, TEXAS.

POCKET-CLOSURE.

No. 926,530.

Specification of Letters Patent.

Patented June 29, 1909.

Application filed August 29, 1908. Serial No. 450,859.

To all whom it may concern:

Be it known that I, JOHN W. WILKINSON, citizen of the United States, residing at Beaumont, in the county of Jefferson and State of Texas, have invented certain new and useful Improvements in Pocket-Closures, of which the following is a specification.

My invention relates to new and useful improvements in pocket closures.

10 The object of the invention is to provide a pocket closure embodying two flaps secured to the opposite walls of the pocket and secured together to prevent access to the pocket without first detaching the lower ends of the flaps.

Finally the object of the invention is to provide a device of the character described that will be strong, durable and efficient, and simple and comparatively inexpensive to 20 produce, also one in which the several parts will not be liable to get out of working order.

With the above and other objects in view, the invention has relation to certain novel features of construction and operation, an 25 example of which is described in the specification and illustrated in the accompanying drawings, wherein:

Figure 1 is a sectional view of a pocket showing my invention applied thereto, Fig. 30 2 is an inner elevation of one side of the pocket, and Fig. 3 is a similar view of the opposite side.

In the drawings the numeral 1 designates the fabric of the garment or other article to 35 which the pocket is attached, or in other words forms one wall of the pocket.

2 designates the fabric or material which is applied to the part 1 to form the pocket and constitutes the other wall of the pocket.

40 The invention resides more particularly in the provision of flaps 3 and 4 having each a comparatively broad upper edge and tapered or contracted toward its lower end. The upper edge of each flap has a length sufficient 45 to substantially extend the inner length of the pocket.

The flap 3 is secured at its upper end to the wall 2 and the flaps 4 to the wall 1 as shown in Fig. 1. These flaps are secured to the pocket by turning opposite hems 5 thereon and securing these hems to the walls of the pocket, thus leaving flap hanging smoothly in the pocket with plain opposed surfaces.

Near the lower ends of the flaps a resilient 55 fastening or means of securing the ends together is provided. In carrying this out, a socket 6 is secured to the lower end of the flap 4 and a fastening head 7 adapted to enter the socket 6 is secured to the lower end of the 60 flap 3 so that access to the pocket below the point where the head enters the socket is prevented. When it is desired to gain access to the pocket, it is only necessary to use one hand in releasing the fastening and the flaps. 65

It is to be noted that the arrangement of the socket and head may be reversed and that other styles of fastenings may be substituted and also that the closure may be applied to hand bags, satchels and other devices as well as pockets.

What I claim, is:

In a pocket closure, two flaps, each secured at its upper end to one of the walls of the pocket, the flaps hanging free on opposite sides of the pocket and their free lower ends being unconnected, and a resilient fastening for temporarily securing the lower ends of the flaps together, one part of the fastening carried by one flap and the other 75 part of the fastening carried by the other flap, the flaps adapted to be extended from the pocket and their ends entirely separated.

In testimony whereof I have signed my name to this specification in the presence of 85 two subscribing witnesses.

JOHN W. WILKINSON.
